Primary Examiner — Robin V Webster*Assistant Examiner* — Keith J Wilson(74) *Attorney, Agent, or Firm* — Daryl R. Wright; Greg Carr(57) **CLAIM**

We claim the ornamental design for a wheel for a model vehicle, as shown and described.

DESCRIPTION

FIG. 1 is a top, left, front perspective view of a wheel for a model vehicle;

FIG. 2 is a top, right, rear perspective view thereof;

FIG. 3 is a left elevation view thereof;

FIG. 4 is a top plan view thereof;

FIG. 5 is a right elevation view thereof; and,

FIG. 6 is a top, left, front perspective view of the wheel for a model vehicle mounted on a model vehicle platform.

The broken line showing of the model vehicle platform is provided for the purposes of illustrating environmental structure and forms no part of the claimed design.

The broken lines depicting the interior of the wheel illustrate portions of the wheel for a model vehicle that form no part of the claimed design.
